UNITED STATES PATENT OFFICE.

JOHN O. MORRIS, OF WASHINGTON, DISTRICT OF COLUMBIA, ASSIGNOR TO THE MORRIS
SPECIALTY MANUFACTURING COMPANY, OF SOUTH DAKOTA.

FARE-REGISTER.

No. 895,880.

Specification of Letters Patent.

Patented Aug. 11, 1908.

Application filed November 12, 1907. Serial No. 401,884.

To all whom it may concern:

Be it known that I, JOHN O. MORRIS, citizen of the United States, residing at Washington, District of Columbia, have invented 5 certain new and useful Improvements in Fare-Registers, of which the following is a specification.

My invention relates to fare registers for use in street cars and in like situations, the 10 invention being designed to prevent fraud on the part of the conductors, who collect the fares, and the invention comprises means associated with the fare register by which the attention of the passengers, and particularly 15 the one who has just paid his fare, will be attracted to the fare register, and particularly to the act of the conductor in ringing up the fare, so that the conductor will be deterred from omitting to do this with the intention of 20 appropriating the fare to his own use.

In carrying out my invention I provide means whereby at irregular intervals, or more properly speaking, after a number of fares have been rung up a sign ticket or like device 25 will be displayed by the operation of ringing up the last fare, which sign or ticket will entitle the passenger whose fare has just been rung up to an award of some character, such as a ticket or a number of tickets, or a free 30 pass on the road. Of course, the interval between the display or the ejection of the award is made variable so that neither the passenger nor the conductor will know when the award devices will eject or display the award or sign, 35 and in this way the attention of the passengers will be constantly directed to the fare register and to the work being performed by the conductor, thus deterring him from carrying out any fraudulent intentions.

40 In connection with the award displaying or delivering mechanism and the fare registering mechanism, I provide locking means so that when the awarding or displaying mechanism is operated the apparatus will be 45 locked and will require the conductor to perform a specific act in releasing the mechanism for subsequent operations and the locking operation will prevent the conductor from proceeding with the ringing up of fares 50 until after he has delivered the award to the proper person and has then reset the parts for another operation.

One result of the use of my invention will be to induce or force the conductors to ring up the fares separately, for as they do not 55 know at what moment the award will be displayed and the mechanism locked they will of necessity, in order to deliver the award to the proper person, have to ring up the fares separately as they will be in constant expectation of the display of the award or the ejection thereof from the apparatus. 60

My invention consists in the features and combination and arrangement of parts hereinafter described and particularly pointed out 65 in the claims.

In the accompanying drawings, Figure 1 is a face view of the award ejecting or displaying mechanism, part of the frame and dial being omitted. Fig. 2 is a view looking 70 in the same direction as Fig. 1 showing the mechanism which lies below the frame plate shown in Fig. 1. Fig. 3 is a detail view on a reduced scale of the dial with the sign in position displaying the blank at the display opening. Fig. 4 is a similar view to Fig. 3 with the sign in position to call attention to the fact that the awarding mechanism has been operated. Fig. 5 is a detail view of an operating pawl for the awarding mechanism. 75 Fig. 6 is a sectional view substantially on the line 6—6 of Fig. 2 but with some of the parts shown in Fig. 1 omitted. Fig. 7 is a detail view of the award ejecting wheel and the chute and supply roller. Fig. 8 is a detail view of the part of the casing showing means for locking the case. Fig. 9 is a diagrammatic view showing the connections between the awarding or ejecting mechanism and the fare register and showing also means 80 by which a signal is sounded or displayed at the end of the car opposite that at which the register or award displaying or ejecting mechanism is located. Figs. 10 and 11 are 85 views of details.

Referring first to Fig. 9, 10 indicates a fare register of any ordinary standard form. 11 indicates generally the detector or award displaying or ejecting mechanism which is operated through a link 12 from the lever 13, 100 which in turn is operated by the fare register cord 14 in any ordinary manner. The operation of this lever 13 serves to operate the fare register and to simultaneously give one ac-

tion or movement to the award displaying mechanism. The link 12 connects with a slide 15 arranged to move between gib 16 fixed to the bottom plate 17 of the casing 18 which contains the mechanism for displaying or ejecting the award or both, and also the means for locking the apparatus together with the fare register when an award has been displayed or ejected and is to be delivered to the passenger whose fare has just been rung up. The slide 15 has inclines or cam edges 19 thereon operating against a roller 20 on a slide 21 moving in guides 22 on the said base 17 the said slide 21 carrying a pawl 23 under tension of a spring 24 and engaging a toothed wheel or ratchet 25. This toothed wheel is located below the intermediate frame plate 26 arranged within the casing and is therefore shown in dotted lines in Fig. 2. The shaft of this wheel extends up through the frame plate 26 and carries at its upper end above the said frame plate, a disk 27 having teeth 28 thereon adapted to engage recesses 29 in a disk 30, which is also journaled to the plate 26 and has teeth portions 29' to engage recesses in a similar power transmitting wheel 31 which in turn transmits movement to a disk or wheel 32, both of these disks being also journaled in the frame plate 26. The disk 32 has associated therewith a worm gear 33 meshing with a worm gear 34 on a shaft 35 journaled in bearings 36 on the frame plate, the said shaft carrying a pin wheel 37, the peripheral pins or teeth of which, as shown at 38, are arranged to engage openings in the ticket strip, said strip being indicated at 40 and the openings at 41. This ticket strip is rolled on a supply drum 39 and on its way to the delivery opening at 42 it passes along a chute or guide 43 which directs it and holds it in proper position to be engaged by the pins 38 so that the revolution of this wheel will feed the ticket strip outwardly through the mouth 42 and the times at which this ejecting operation will be performed depends of course upon the relation of the intermeshing wheels to each other.

The teeth and the recesses on the transmitting wheels 27, 30, 31 and 32 are irregularly disposed so that the toothed feed wheel for the ticket strip will be moved at irregular intervals to eject the award or ticket from the case. These tickets have printing thereon indicating the value of the award each being good for one or more car tickets or passes on the road, and these tickets may have thereon, for instance, the letters S and L, the letter S standing for a school ticket and the letter L for a labor ticket, the object being by punching at either letter to give to the passenger an award corresponding in value to the rate of fare paid, that is to say, a cash fare will secure an award of the ticket equal to a cash fare and a school ticket will consti-

tute an award equal to the value of a school 65 ticket and so with the labor ticket, the conductor punching the appropriate letter.

After each operation the slide 15 returns to normal position shown in Fig. 2, ready for another operation, this returning movement 70 being due to the action of the spring 43' forming a part of the fare register mechanism. The disks 30, 31 and 32 when moved are locked in position by the locking surfaces as at 44 on one disk engaging the periphery 75 of the adjacent disk, this locking effect holding the disk in position until it is positively operated by the tooth on the adjacent disk. The slide 21 is returned to normal position by means of a spring 45, (see Fig. 5) this 80 spring being contained in a recess in the slide.

In order to lock the award delivering mechanism and the fare register against operation when an award is delivered or displayed I provide a locking slide 46 suitably guided in a cutaway portion of the gib at 47 and by a screw and slot 48, the said slide being under tension of a spring 49 and having its projection 50 arranged to engage an opening 51 in the actuating slide 15 when the said locking slide is free to move. Said slide is held normally inactive by a detent 52 engaging a pin 53, carried by an arm 54 on the slide, the end of said detent being in the path of the teeth of a wheel or disk 55, which disk or wheel is arranged on the lower side of the frame plate 26, but is connected with the disk or worm wheel 33 by means of a pin or shaft. This toothed wheel moves with the 100 disk 32 and when so moved one of its teeth presses the detent 52 aside releasing the pin 53 and the locking slide 46, which, under the action of spring 49, will engage, by its projection 50, the recess 51 in the actuating 105 slide 15 and thus hold said slide against movement until the conductor by a specific act or operation resets the lock after having given the ejected ticket or award to the proper passenger. The detent 52 is under tension of a spring 56. By the use of the awarding mechanism and the lock which operates each time that an award is displayed or delivered, the conductor is induced or forced to register the fares separately as they 115 are collected, instead of permitting him to collect a large number of fares and ring them up by a series of actions closely following each other. For as the awards are displayed or ejected at irregular intervals the conductor does not know the moment when the award will be delivered from the apparatus and the said apparatus locked, and to avoid confusion he must of necessity ring up the fares as collected, and as soon as the apparatus 120 is locked he must stop the collection of fares and deliver the award to the proper person and then by resetting the lock he will be per-

mitted to proceed with the registration of other fares. The lock is released or reset by a lever 57 pivoted at 58 to a part of the frame and having a link connection 59 with the 5 locking slide. The toothed wheel 55 also sounds an alarm or signal bell for which purpose the tooth of said wheel operates a lever 59' pivoted to the frame at 60 and connected by a link 61 with the arm 62 of a bell hammer 63, said hammer being adapted to operate against a bell 64. This lever 59' is arranged substantially diametrically opposite the detent 52. By the operation of this signal the attention of the passengers will be 15 directed to the display of the award or its ejection from the apparatus.

I provide means for registering the number of awards displayed or rejected, this supplemental registering mechanism being arranged 20 within the casing 18 of the awarding mechanism and being inaccessible to the conductor or operators of the road. This registering mechanism comprises an arm 65 attached to the shaft 66 of the registering mechanism 67, this registering mechanism being of any ordinary standard pattern as shown generally in Fig. 1. The arm 65 extends downwardly and its forked end engages a pin 68 carried by an arm 69 on the locking 25 slide 46 so that each time this locking slide is operated, which of course corresponds to the times at which the awards are ejected, the registering mechanism 67 will be operated to keep account of the awards delivered. These tickets of award are numbered and the authorized officer of the company can 30 ascertain at any time whether the registrations by the registering mechanism 67 corresponds with the number of awards delivered.

In order to provide a visible signal or sign I employ an upper plate or dial 71, Figs. 3 and 4, which covers all of the operating mechanism. This plate is provided with an 45 opening 71 through which a shutter 72 is visible and above the opening 70 the dial bears the words "Watch for free" and below the opening the word "here" appears. The movable shutter 72 is carried upon the 50 front end of a shaft 73 which extends through the hollow shaft of the disk 32 and carries on its front end an arm 74, the end of which has a pin 75 entering the forked end of an arm 76 which is connected with the arm 77 carrying the shutter and which arm is pivoted to the dial or cover plate at 78. The inner end of the shaft 73 has rigidly affixed thereto, an arm 79 which is pivotally connected with a link 80, the other end of which is pivoted 55 to the locking slide at 81 so that each time the locking slide is moved to lock the slide 15 against action the shutter 72 will be operated through the shaft 73 and the described lever link and arm connections so

that the word "tickets" which is carried by 65 the said shutter, will be brought to the opening 71 of the dial or cover plate to be displayed, and as this action occurs at the same time that the bell is sounded the attention of the passengers is directed to the sign 70 and to the pointer or hand which the dial bears at 81, which points to the ticket or award projecting from the casing.

I do not limit myself, of course, to any particular form of award, as various devices 75 may be employed to be ejected from the casing. The casing 18 is supported by a backing frame 82 which is connected with any suitable point in the car, and said casing is locked to said frame by a latch 83 pivoted 80 at 84 on the casing and passing through a lug 85 on the backing frame. This latch 83 is provided with an opening which may receive any suitable form of pad-lock, the key of which is held by the authorized officer of 85 the company. The casing has an upper rim 86 with an inwardly projecting flange 87 bearing upon the glass 88 which is supported by the pins 89. This rim is connected with the casing by means of a bayonet 90 slot 90, dotted lines, Fig. 8, formed in the main shell of the casing, said bayonet slot receiving a projection 91 on the rim 86 so that by turning the rim circumferentially from the position shown, Fig. 8, pin 91 may 95 be removed from the bayonet slot to thus permit the rim of the casing to be removed therefrom. In order to prevent, however, the circumferential movement of the rim except by authorized persons, I provide a 100 locking bolt 92 embedded in the casing and having a pin 93 projecting therefrom to enter a notch in the lower edge of the rim. This locking bolt is held in normal position to hold the rim against circumferential movement by a pin 94 which at its inner end is adapted to bear upon the face of the backing frame 82 and so long as this pin bears against the backing face the bolt will be held in its uppermost position with the pin 92 engaging 105 the notch in the rim. A spring 95 is interposed between the bolt and the pin 94 tending to press the bolt outwardly. It will be seen from this construction that so long as the casing is locked to the backing frame by 110 the latch 83, the rim 86 will be held against circumferential movement by the pin 92, but as soon as an authorized person unlocks the casing from the backing plate at the latch 83, the casing can be separated and the pin 94 will no longer be held by bearing against the face of the backing plate and the bolt can be pressed inwardly to release the pin from the notch in the rim.

In order to provide a signal at the end of 125 the car opposite that at which the fare register or detector or awarding mechanism is arranged, I provide a bell 96, and if desired, a

lamp 97 at the other end of the car, these parts being in circuit with a suitable battery 98, the circuit of which is closed with an arm 99 on the locking slide engaging contacts 5 100, 101 on the frame.

The pins 89 for supporting the glass plate may be spring pressed to avoid breakage of the glass. I may, if desired, support the dial or cover plate by centrally disposed arms 102 10 extending up from the standard 103.

By means of the perforated ticket strip and the wheel having the pins thereon, fraud cannot be perpetrated by any one attempting to pull out through the discharge mouth 15 the end of the ticket strip, for the toothed wheel being held in fixed position by its worm gearing will simply tear the ticket strip and prevent any perfect tickets from being secured.

20 It will be observed that the award delivering mechanism is independent of the fare registering mechanism in that it may be employed with any form of fare register without requiring change therein.

25 The awarding mechanism is complete in itself and may be set up along side of the ordinary register mechanism.

I claim as my invention:—

30 1. In combination in an awarding mechanism for use with fare registers, a reciprocatory slide having an incline or inclines thereon and having connection with the fare registering mechanism, means for delivering an award and connections between the said delivery means and the said slide comprising the supplemental slide operated by inclines on the main slide and pawl and ratchet mechanism operated by the supplemental slide, substantially as described.

40 2. In combination in an awarding mechanism for use with fare registers, a slide having an incline or inclines, a supplemental slide operated by the said incline, award delivering means and connection between the supplemental slide and said award delivering means, substantially as described.

45 3. In combination in an award delivering means for use with fare registers, a wheel having pins or teeth on its periphery to engage the awarding devices and means for operating the said pin wheel at intervals and by the operation of the fare register mechanism, substantially as described.

50 4. In combination with fare registering mechanism, an award delivering means comprising a wheel having pins on its periphery to engage the awarding devices and means for operating the said pin-wheel at intervals, the said pin wheel being located adjacent the discharge opening for the award devices, substantially as described.

55 5. In combination in an award device for use with fare registers, a pin wheel with means for operating the same to eject the award, a

chute adjacent the periphery of the pin 65 wheel through which the awards pass, and means for driving the pin wheel at regular intervals, said means serving to hold said wheel against movement should the award be pulled outward substantially as described. 70

6. In combination with an award delivering or display means for use with fare registers, a slide with connections for operating the same when the fare register is operated, connections between the said slide and the 75 award delivering means, the said slide being adapted to operate the said connections when moved in either direction, substantially as described.

7. In combination with an award delivering means for use with fare registers, a slide with means for operating the same when the fare register is operated, a supplemental slide moving at right angles to the main slide and operated by the said main slide and connections from the supplemental slide to the award delivering means, substantially as described. 80

8. In combination with an awarding mechanism for use with fare registers, a slide 90 with connections for operating the same when the fare register is operated, connections operated by the said slide for operating the awarding mechanism and a lock with means for operating the same automatically, 95 said lock engaging a part of the slide, substantially as described.

9. In combination with an awarding mechanism for use with fare registers, a slide with means for operating the same when the fare 100 register is operated, awarding mechanism, a train of wheels between the said slide and awarding mechanism for operating the same, a lock for the awarding mechanism and means for operating the said lock from the 105 movement of the said train of wheels, substantially as described.

10. In combination with an awarding mechanism for use with fare registers, connections for operating said awarding mechanism, locking means therefor, a detent for holding the said locking means inactive, a toothed wheel for operating the detent and a slide forming a part of the operating connection for the awarding mechanism, the said 115 lock when released engaging the said slide, substantially as described.

11. In combination in an awarding mechanism for use with fare registers, a slide with means for operating the same when the fare 120 register is operated, awarding mechanism, a train of wheels between the said slide and the awarding mechanism, a lock, a toothed wheel operated from the said train of wheels and means for controlling the lock from the operation of said toothed wheel, substantially as described. 125

12. In combination in an awarding mech-

- anism for use with fare registers, a slide to be operated when the fare register is operated, awarding mechanism, a toothed wheel connected with the awarding mechanism to be operated thereby and a sliding locking device, the said toothed wheel controlling the said sliding locking device, substantially as described.
13. In combination in an awarding mechanism for use with fare registers, a slide to be operated when the fare register is operated, awarding mechanism, a supplemental slide operated from the main slide and connected with the awarding mechanism, a sliding lock to engage the main slide, a detent and a toothed wheel operating with the awarding mechanism for releasing the detent to allow the sliding lock to engage the main slide, substantially as described.
14. In combination in an awarding mechanism for use with fare registers, awarding means, a main operating member in connection with the fare register to be operated thereby, a train of wheels between the same and the awarding device including a toothed wheel and a pawl for operating the same, a main frame plate in front of which the train of wheels is located, excepting said toothed wheel, a lock arranged in rear of the frame plate and a toothed wheel connected with the train of wheels and located in rear of the said frame plate for controlling the lock, substantially as described.
15. In combination a main slide, a frame plate in front of the same, a train of wheels on the front side of the frame plate, a pawl and ratchet connection between the said slide and the train of wheels, said pawl and ratchet connection being on the rear side of the plate, a sliding lock for engaging the main slide on the rear side of the said frame plate and a toothed wheel for controlling the lock, said toothed wheel being located on the rear side of the frame plate and connected with a train of wheels on the front side thereof, substantially as described.
16. In combination with an awarding mechanism for use with fare registers, locking means for the awarding mechanism, an alarm and a toothed wheel for controlling the locking mechanism and the alarm, substantially as described.
17. In combination in an awarding mechanism for use with fare registers, awarding means with operating connection thereto, a dial and shutter having a sign displayed thereon and means for operating the said shutter to display the said sign when the awarding means is operated, substantially as described.
18. In combination in awarding mechanism for use with fare registers a fare register, connections operated with the fare register, awarding means operated thereby for presenting an award and a register connected with the awarding means to register the number of awards ejected, substantially as described.
19. In combination, awarding mechanism, connections for operating the same, a lock for the said connections, a register to register the number of actions of the awarding mechanism, and means for operating the said register from the locking device, substantially as described.
20. In combination with awarding mechanism, a sliding locking device, and a register operated by said sliding locking device.
21. In combination with awarding means, a display shutter pivotally supported, connections to the awarding means including a train of wheels, one of which has a hollow shaft, a shaft passing through the said hollow shaft and connected with the shutter, and means for operating the said shaft when the awarding means is operated, substantially as described.
22. In combination, a shutter, awarding means, and locking means to be set when the awarding means is operated, said locking means operating the shutter when the locking means is set, substantially as described.
23. In combination with awarding means, a shutter, a register to indicate the number of operations of the awarding means, a lock to be set when the awarding means is operated, the said shutter and register being operated from the said lock, substantially as described.
24. In combination in awarding mechanism for use with fare registers, award presenting means with connections for operating the same when the fare register is operated, a signal device arranged at a point distant from the awarding means electric circuit connections from the awarding mechanism to the said signal device, and means for closing said circuit when the awarding mechanism is operated, substantially as described.
25. In combination, awarding mechanism, connections for operating the same when the fare register is operated, a lock with means for setting the same when the awarding mechanism is operated, a signal to be arranged at a point distant from the awarding mechanism and means for operating the said signal from the setting of the lock, substantially as described.
26. In combination with a casing, an award delivering or displaying device, connections for operating the same including worm gearing whereby the said device will be held against movement except through the said worm gearing, substantially as described.
27. In combination with a casing, a frame plate, an award delivering device, in front of said frame, a train of wheels for operating

the delivery device, said wheels being exposed on the front side of the frame plate and being adapted to be interchanged with other wheels, substantially as described.

5 28. In combination with the device for delivering the award, a train of wheels for operating the said device having projections, and recesses for driving one from the other and the flat surfaces of the wheels to lock the

same to adjacent wheels, substantially as described. 10

In testimony whereof, I affix my signature in presence of two witnesses.

JOHN O. MORRIS
